Primary Examiner — Carla Jobe Wright(74) Attorney, Agent, or Firm — Chiesa Shahinian & Giantomaso PC(57) CLAIM

The ornamental design for a mobile telephone case, as shown and described.

DESCRIPTION

FIG. 1 is a bottom right front perspective view of a mobile telephone case according to our design;

FIG. 2 is a bottom left rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depict environmental subject matter that forms no part of the claimed design.
